(57) **CLAIM**

The ornamental design for the pan, as shown and described.

DESCRIPTION

FIG. 1 is a top view of the pan according to my new design;

FIG. 2 is a right-side view thereof;

FIG. 3 is a perspective view of the back side and bottom side

thereof;

FIG. 4 is a perspective view of the right side and bottom side

thereof; and,

FIG. 5 is a bottom view thereof.

The broken lines shown in the drawings represent portions

of the pan that form no part of the claimed design.
